UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

PUSH-BUTTON SWITCH.

1,295,913.

Specification of Letters Patent.

Patented Mar. 4, 1919.

Application filed May 18, 1914, Serial No. 839,215. Renewed November 4, 1918. Serial No. 261,146.

To all whom it may concern:

Be it known that I, RAY H. MANSON, a citizen of the United States, residing at Elyria, in the county of Lorain and State of Ohio, have invented certain new and useful Improvements in Push-Button Switches; and I do hereby declare the following to be a full, clear, and exact description of the invention, such as will enable others skilled in 10 the art to which it appertains to make and use the same.

My invention relates to push button switches for controlling electric circuits, and especially for devices of this kind which are 15 employed for operating the warning signal apparatus of automobiles, motor cycles and other vehicles.

The particular object of my invention is to provide a switch of the type mentioned 20 which is easily operated, no matter where the button is touched. In the use to which I have referred, though of course I am not limited thereto, the driver must keep his attention upon the operation of the machine, 25 and consequently, has no time to look at the button when he operates it. It is also desirable that the warning signal should be operated immediately. With many of the old type of buttons, the operator always has to 30 take time to look at the button; consequently, this style of button, when employed upon automobiles, frequently causes dangerous delay in the operation of the horn.

By my invention, I overcome these obstacles, and provide a button which can be easily touched without looking at the button, and which will operate the switch no matter which part of the button is touched.

Other objects of my invention and the invention itself will probably be better understood from a description of an embodiment of the invention.

The figure illustrates one embodiment of my invention.

Referring now to the drawing and to the embodiment illustrated therein, at 1 I show a frame member, which here consists of a cylindrical shaped casing. At 2 is shown a base member, which here consists of insulating material, inclosed within the member 1 and held securely in position by lugs 3 on the casing, which may be formed integral therewith and which bite into the insulating material. The member 2 is formed with a 50 chamber 4, here shown as cylindrical in shape, and extending clear through the

member 2, the upper portion of the chamber being of less diameter than the lower portion. Catch means 6 are provided upon the casing and are here shown as integral therewith, being formed by turning inwardly the upper edge of the casing 1. I have shown the catch member 6 as extending all around the periphery of the casing, but it may readily be formed in any other suitable manner. 60 The terminals of an electric circuit are shown at 7 and 8, each consisting of a screw driven into the insulating member 2, and insulated each from the other thereby. These screws may be provided with washers 9 and 10 separated from each other. At 11 is shown the push button which may be of any suitable form. I here show it of greater area than the stationary member and of umbrella shape, having an annular groove 12 70 into which the upper parts of the casing fit when the button is depressed. A catch member 13 is provided for the push button, here shown consisting of an annular plate co-operating with the catch member 6 upon the 75 stationary member and normally held in engagement therewith by a spring 14 which abuts at one end against a bearing surface 15 in the button 11, which may be formed by a bearing plate. The other end of the spring 80 abuts against a bearing surface formed in the stationary member, here shown between the screws 7 and 8. The member 13 is connected to the button 11 by suitable means, such as screws 20. 85

The switch which includes the contacts is carried partly upon the stationary member and partly upon the movable member. In the form shown this switch consists of the two contacts illustrated and a member 30, here 90 shown as a pin connected at one end to the movable member 11 and extending through the coil of the spring 14, having an end 31 projecting therefrom.

As will be seen, the movable member 11 100 presents a large area to the operator. If the operator presses upon the central portion of the member 11, it will descend in a substantially horizontal position, that is, the member 11 will descend substantially parallel to 105 the member 1 until the end 31 of the member 30 engages the washers 9 and 10 which are electrically connected with the terminals of the electric circuit, thereby closing the switch and causing the operation of the 110 signal. If the button is depressed upon the edge, say for example, at the point 40, the

edge 40 will descend about the point 41 as a pivot or fulcrum, the curved point of the pin engaging the washers 9 and 10 and closing the circuit. The point 31 of this pin is formed with a curved area, preferably hemispherical in shape, so that no matter whether the pin descends in a straight line or is inclined and descends, the switch will be readily operated and the circuit closed.

- 10 At 50 is illustrated a signaling device, at 60, a source of current, and at 70, 71 and 72, the conductors which are employed to connect the signaling device, the source of current and the switch in an electric circuit. As 15 will be seen, the catches 6 and 13 form a plurality of loose fulcrums which permit the tilting of the button, no matter upon what point of the edge it is depressed, and at the same time, permits a depression of the button when it is depressed upon the center. With this arrangement, the button responds to slight pressure, no matter where it is applied thereto.

I have shown this embodiment of my invention, not that I wish to be limited to this form or to the details thereof, as I contemplate numerous and extensive departures from such form and details, the invention being more particularly set forth in the appended claims.

I claim:

1. In a circuit controller, the combination of a cylindrical casing having a catch member formed on the open end thereof by turning inwardly the upper edge of the casing, a block of insulating material within the casing having a chamber therein, a pair of electrical terminals in said chamber separated and insulated from each other, a push button 25 of relatively large area, a plate fastened upon the bottom of the push button, said plate being within the casing and a spring normally holding the edges of the plate against the under side of the turned over edges of the casing, permitting either depressible or tilting movement, said spring located between the push button and the member of insulating material, and a pin carried by the push button having a substantially hemispherical point adapted to connect the elec-

trical contacts together when the push button is either depressed or tilted.

2. In a device of the class described, the combination of a push button, catch means thereon, a base, catch means thereon, an electric switch comprising a plurality of switch contacts and a switch closing member having a semi-globular point, said member carried by said button, said catch means permitting rectilinear and tiltable movement engaging with each other at a plurality of points to hold said switch normally in switch open position and yielding means between said button and base, said button when pressed on an edge rocking about a point of engagement of said catch means and when pressed in the center descending substantially parallel to the base to operate said switch.

3. In a circuit controller, the combination of a base, a pair of normally open electrical contacts mounted on said base, a push button 75 slidably connected to said base, means to slidably and rockably connect the button to the base including an annular catch on each of the button and the base, said button being tiltable about said catch members when depressed, and a member depending from the center of the under-side of the button adapted to connect said contacts when the button is either depressed or rocked about said catch members.

4. In a circuit controller, the combination of a base, a pair of electrical contacts mounted on the base, an annular inwardly turning flange on the base, a push button having an annular outwardly extending flange, said flanges loosely engaging to permit rocking movement, yielding means for normally holding said flanges in engagement, and a member projecting from the central portion of the button for connecting said contacts when the button is either depressed or rocked.

In witness whereof, I have signed my name in the presence of two witnesses this 11th day of May, 1914.

RAY H. MANSON.
